PROCESS AND APPARATUS FOR
DISPENSING GASOLINE

John O. Eisinger, Hammond, Ind., assignor to
Standard Oil Company, Chicago, Ill., a corpora-
tion of Indiana

Application February 13, 1932, Serial No. 592,694

13 Claims. (Cl. 221—96)

This invention relates to the dispensing of motor fuel and more particularly to a process and apparatus for simultaneously blending a plurality of naphthas and dispensing a gasoline of constant performance characteristics in accordance 5 with the prevailing temperature at the time of dispensing.

Blended gasoline, as sold on the market of today, is usually prepared at the refinery by blending several types of naphthas until a gasoline has been obtained with the desired volatility characteristics and combustion properties most suited for the yearly average temperature prevailing in the section of the country where the gasoline is to be used. However, it has been found that gasoline with volatility and combustion characteristics suitable for summer will not be suitable for winter, and vice versa, as will be explained hereinafter. Some refineries make a winter gasoline for cold weather use and a summer gasoline for hot weather, that is, a gasoline having the most desirable combustion and volatility characteristics for the average temperature during the particular season. Generally, the winter 10 gasolines are prepared so that about 15 to 20% of the gasoline will distill off in an Engler distillation at 158° F., and the summer gasolines are prepared so that about 8 to 14% of the gasoline will distill at 158° F. These percentages may be varied somewhat but the above ranges give satisfactory results. The percentages of gasoline volatile at 158° F. gives a very satisfactory and 15 convenient indication of the performance characteristics of a gasoline with respect to starting and acceleration of a motor vehicle.

It is apparent that the above methods for preparing gasoline adaptable to the average yearly or seasonal temperature prevailing at the place of consumption are not capable of producing a gasoline that will be suitable for the high and low 20 temperatures occurring during the year or during the summer or winter seasons. For example, the average summer temperature for a particular section of the country may be about 75° F., but many summer days may be as hot as 95 to 100° F. A gasoline which is prepared for use where the average temperature is about 70° F. should contain about 14% of hydrocarbons volatile at 158° F. and should have a Reid vapor pressure of 25 about 8 to 10 pounds per square inch, but during the hot summer days the vapor pressure of such a gasoline will become very high. Consequently, when this gasoline is used on hot days the high vapor pressure will cause vapor locking in the 30 fuel induction system and carburetor and will

seriously interfere with engine operation or even cause the engine to stall. Stalling is particularly apt to occur when the engine is running at idling speed, as at stop signals, railroad crossings, etc.

A winter gasoline may be prepared for use at an average temperature of about 40° F. but many winter days may be as cold as 0° F. A gasoline suitable for a temperature of about 40° F. should contain about 20% of hydrocarbons volatile at 158° F., but for use at 0° F. it must contain a much larger proportion of such light material, for example, about 34% of the hydrocarbons should be volatile at 158° F. If a gasoline which contains about 20% of hydrocarbons volatile at 158° F. is used in a motor vehicle at about 0° F., great trouble will be encountered when starting said motor.

The above data relating to the percentages of gasoline that should be volatile at 158° F. in order that the gasoline will possess good combustion properties at various temperatures, were determined experimentally by using a large variety of 20 blends in automobiles and observing their starting and accelerating characteristics.

It is the object of my invention, therefore, to provide a process and apparatus for blending or mixing a plurality of naphthas at the dispensing pump and at the time of dispensing, so as to produce a gasoline with the most suitable performance and volatility characteristics for the temperature prevailing at the time of dispensing said gasoline. By blending the naphthas at the time of dispensing, the volatility of the gasoline can be accurately adjusted to conform with the 30 prevailing temperature, and the resulting gasoline will have the most suitable performance characteristics for use at the existing temperature. Also, certain types of motor vehicles may require a special blend of gasoline, that is, a 35 gasoline with a volatility at 158° F. which is above or below the volatility generally required for most motor vehicles, and by my invention I can easily adjust the dispensing pump so that a gasoline with the desired volatility can be supplied.

My invention will be more clearly understood when the following description is read in connection with the following drawings in which:

Figure 1 represents an elevational view of an 50 adjustable gasoline dispensing pump, showing the blending valve and naphtha storage tanks.

Figure 2 represents a vertical cross section of the blending valve and thermally responsive element for operating the said valve.

40 Figure 16 shows the ball bearing and race on the thrust bearing.

Figure 17 represents an elevational view of the fork used on the operating levers.

45 Figure 18 represents an end view of the fork used on the operating levers.

Briefly, the broad concept of my invention can be obtained from Figure 1 which shows a gasoline dispensing pump 10, comprising a meter and counting device 11, a visible flow-gauge 12, and 50 a hose 13 leading to the hand controlled dispensing nozzle 14. A motor 15, located in the lower part of the dispensing pump, is adapted to drive the rotary pump 16 by the belt or chain 17. The rotary pump draws light and heavy naphthas 55 from the constant level supply tanks 18 and 19 respectively to the blending valve 20 where the two naphthas are mixed in proportions to give a gasoline with the most desirable combustion and volatility characteristics suitable for the prevailing temperature. The blending valve 20 is controlled in accordance with the prevailing atmospheric temperature, by the thermally responsive element contained in casing 21.

60 The blending valve and thermally responsive element for regulating the same is shown in detail in Figure 2. The blending valve 20 comprises threaded inlets 22 and 23 where the two naphthas pass into the blending valve, and an outlet 24 which leads to the rotary pump or propelling means 16. A tapered orifice 25, formed by shoulders 26 and 27, is placed between each inlet 22 and 23 and the outlet 24. The two orifices 25 may be of the same diameter or they may have different diameters, depending upon the design of 70 the blending valve. A valve rod 28, carrying the

orifice plugs 29 and 30, passes lengthwise through the blending valve and is slidably mounted in the bearings 31, 32 and 33. The bearing 31 is held in position by the web member 34, as shown in Figures 2 and 4. The movement of the orifice 5 plugs 29 and 30 in the orifices 25, provides the means for controlling the proportion of light and heavy naphtha that flows through the blending valve 20. Bearing 32 is supported by the member 32a, as shown in Figures 2 and 5. Bearing 33 10 is contained in the plug 35 which separates the thermally responsive element from the proportioning valves. The end of the valve rod that rests in bearing 33, passes through the packing gland 36 and is rigidly fastened at 37 to the 15 sylphon bellows 38, which may contain any suitable expansible liquid, vapor or gas. Instead of using the sylphon bellows type of thermally responsive element, any of the numerous well known temperature actuated devices may be used in 20 place thereof. Also, any well known gearing device may be interposed between the sylphon bellows 38 and valve rod 28 so that a small movement of the bellows will cause a greater lateral movement of the valve rod, if desired. The casing 21, which may be of non-heat conducting material, screws onto the blending valve at 21a and surrounds the sylphon bellows 38. Slots 38, shown in Figure 1, are provided in the casing 21 so that air has free access to the bellows contained in said casing. When the blending valve 25 is in operation, an increase in the temperature of the surrounding air causes the sylphon bellows or thermally responsive element to expand and push the valve rod 28 to the left, viewing Figure 2, thereby moving the orifice plug 30 into the orifice opening 25 and decreasing the flow of liquid therethrough; also orifice plug 29 is moved away from the other orifice opening 25, thereby permitting an increase in the flow of liquid through 40 said orifice. The reverse of the above operation occurs when the sylphon bellows contracts; caused by a decrease in atmospheric temperature. It should be understood that the orifice plugs 29 and 30 are adjustable on the valve rod 28 and may be 45 adjusted so that the appropriate amount of naphtha will flow through each orifice when the thermally responsive element has expanded or contracted in response to a change in the atmospheric temperature.

The light and heavy naphtha storage tanks 40 and 41 are usually placed underground near the dispensing pump, or located where they can be easily refilled. The pipes 42 and 43 connect the storage tanks to their respective constant 55 level supply tanks 18 and 19. A float check valve 44 is placed on the end of pipe 42 which projects into the constant level supply tank 18, and a similar float check valve 45 is placed on the end of pipe 43 which projects into the constant level of tank 19. These float check valves control the flow of naphtha from the storage tanks and maintain a constant liquid level within the supply tanks. The constant level supply tanks 18 and 19 should be placed on the same 60 horizontal plane so that the lift from the respective tanks to the blending valve 20 will be substantially the same. This precaution is advisable when the light and heavy naphthas are drawn into the blending valve 20 by a pump operating on the outlet side of said blending valve. The pipes 46 and 47 project into the supply tanks 18 and 19 respectively and terminate under the level of naphtha in said tanks and connect 70 said tanks with the blending valve 20. Check 75

valves 48 and 49 are placed in the pipes 46 and 47 respectively, near the entrance of said pipe into the constant level tanks, for the purpose of preventing the liquids from running back into the tanks when the pump 16 is not running. A vent 18a connects the constant level tank 18 with the storage tank 40, and a similar vent 19a connects the constant level tank 19 with the storage tank 41.

When the dispensing pump is to be used, the valved nozzle 14 is removed from the hook 14a, the motor 15 automatically starts and drives the rotary pump 16, then as soon as the valve on the nozzle 14 is opened, the light and heavy naphthas are sucked from the tanks 18 and 19 through the blending valve 20 where the two are blended in proportions to give a gasoline most suitable for the prevailing temperature conditions. The mixture of naphthas, or gasoline, is then drawn up through the pipe 50 and into the strainer 51, wherein any foreign material is removed and where further mixing may take place if necessary. The gasoline is then forced through the meter and measure device and out the dispensing nozzle 14. The orifice plugs 29 and 30, contained in the blending valves 20, are adjusted on the valve rod 28 so that the siphon bellows will move them into the proper position to give the proportions of naphthas needed to produce the gasoline possessing the most suitable combustion properties adaptable to the prevailing temperature. As the atmospheric temperature changes from hour to hour or day to day, the thermally responsive element 38 is accordingly actuated and thereby varies the proportions of light and heavy naphtha that passes through the blending valve 20. The design of the orifice plugs 29 and 30 or the design of the orifices 25 may be varied so as to effect the amount of flow of naphtha through the orifices. The proportioning valves, which I refer to as an orifice plug and orifice, can be calibrated or set by adjusting the orifice plugs 29 or 30 or by varying the size of the orifice openings 25, so that the flow of naphtha through the orifices will give a blend of light and heavy naphtha possessing a predetermined combustion property for a given temperature. As the two streams of naphtha leave the orifices 25 and enter the outlet 24, they blend with each other and give a substantially homogeneous solution.

For a gasoline to have good performance characteristics, such as easy starting and quick acceleration, the initial boiling point should be at about 95° F., the end boiling point should be at about 400° F., and the Reid vapor pressure should not exceed eight pounds. But the most important point between the initial boiling point and the end boiling point is the amount of gasoline that is volatile at 158° F. The amount of gasoline, or the amount of hydrocarbons, volatile at this temperature in order to give a fuel with good starting and quick acceleration characteristics varies with the temperature at which the gasoline is to be used. For gasolines that are to be used at low temperatures, the amount volatile at 158° F. should be greater than for gasolines used at higher temperatures. For example, the following data shows how a light and heavy naphtha may be blended so that the gasoline produced thereby will possess the desired volatility and performance characteristics for different temperatures at which the gasoline is to be used. Table I shows the Engler distillation of the two naphthas that may be blended in

order to obtain a "performance controlled gasoline."

Table I

Temp. ° F.	Heavy naphtha—% evaporated	Light naphtha—% evaporated
95	0	3
158	1	40
212	17.5	61.5
284	51	84
356	88.3	96
392	99	99

The following table shows the proportions for blending the above light and heavy naphthas, so that the volatility of the gasoline at 158° F. will be most suitable for the temperature at which the gasoline is to be used.

Table II

Air temperature ° F. at which the gasoline is to be used	Percent of gasoline volatile at 158° F.	Percent of heavy naphtha in the gasoline	Percent of light naphtha in the gasoline
-10	37.2	6	94
0	34.5	12.5	87.5
+10	31.4	19.5	80.5
20	28	26	74
30	25.8	33	67
40	23	40	60
50	20	46	54
60	17	53	47
70	14.4	61	39
80	11.5	68	32
90	8.6	76	24
100	6	83	17

It should be understood that the above two tables are given as one example for blending naphthas and are not to be considered as limitations upon the scope of this invention. The above light and heavy naphthas may be blended in other proportions and the percent of hydrocarbons volatile at 158° F. may be varied, but the above tables illustrate blends which give satisfactory results. Also, if naphthas are used that have different Engler distillation characteristics than those shown in Table I, the proportions to be blended must be chosen so that the desired amount of gasoline will be volatile at 158° F. Also, instead of using the 158 point as an index for blending light and heavy naphthas, other points may be chosen, but I have found the 158 point to be a reliable index as to the performance characteristics of a gasoline.

As a modification of my invention, the amount of heavy naphtha used for blending may be constant, and the amount of light naphtha may be varied so that the volatility of the mixture at 158° F. will conform with the above Table II, or to any other desired volatility. Also, the proportions of light naphtha may be constant and the proportion of heavy naphtha may be varied so that the volatility of the mixture at 158° F. will conform with the above Table II, or to any other desired volatility.

Instead of blending the naphthas at various temperatures in relation to their volatility, the naphthas may be blended at the prevailing temperature to produce gasoline with a Reid vapor pressure that obviates vapor locking. Table III gives the approximate proportions of the light and heavy naphthas shown in Table I that may be blended to produce a gasoline with a desirable Reid vapor pressure for the prevailing temperature. The light naphtha of Table I has a Reid

vapor pressure of 19.2 lbs. per sq. inch at 100° F., and the heavy naphtha has a Reid vapor pressure of 6.4 lbs. per sq. inch at 100° F.

Table III.

5

Air temperature °F., at which the gasoline is to be used	Reid vapor pressure in lbs./sq. in. at 100° F.	Percent of heavy naphtha in the gasoline	Percent of light naphtha in the gasoline
20	19.1	1	99
30	17.3	13	87
40	15.6	22	78
50	14.0	34	66
60	12.5	44	56
70	11.1	55	45
80	9.8	67	33
90	8.6	77	23
100	7.5	88	12
110	6.5	99	1

20 The above table is given as one example for blending naphthas in relation to Reid vapor pressure, and it should be understood that the proportions given in Table III are not to be construed as a limitation upon the scope of the 25 invention. Also, if light and heavy naphthas other than those shown in Table I are used for blending, the proportions of said naphthas may be adjusted in order to give the vapor pressures indicated in the second column of Table III, or 30 any other desired series of vapor pressures.

Figure 3 shows a modification of the invention which comprises twin pumps 52 for forcing the naphthas through the blending valve 20. These pumps are driven by a motor 53 through the 35 belts or chains 54. When the lift from the supply tanks to the dispensing pumps is great, it will be found more desirable to force the naphtha through the blending valve, as shown in Figure 3, instead of sucking the naphtha through 40 the blending valve, as shown in Figure 1.

The pumps and motors shown in Figures 1 and 3 may be entirely eliminated if gravity feed is used instead of forced feed. In that case the supply storage tanks are placed above the level 45 of the dispensing pump and the pipe lines 46 and 47 lead directly from the storage tanks to the blending valve. Frequently the gravity feed is used when the terrain near the dispensing pump affords a suitable location for the storage 50 tanks.

Figure 6 represents another embodiment of my invention with a manually operated blending valve used in place of a thermally operated valve. The pipe lines 46 and 47, shown in Figure 6, 55 may be connected to pumps as shown in Figure 3, or they may lead to gravity feed tanks. Also a suction pump may be placed on the exhaust side of the blending valve, for example, one similar to that shown in Figure 1, or twin pumps 60 may be used to force the naphtha through the blending valve, for example, pumps similar to those shown in Figure 3. The naphthas flow into the blending valve, shown in Figure 6, in the same manner as described above with reference to the blending valve shown in Figure 1 65 and are mixed in proportion according to the setting of the proportioning valves.

Figure 7 shows a blending valve similar to the one shown in Figure 2, except that it is manually 70 operated. The left side of the blending valve, viewing Figure 7, is the same as the blending valve shown in Figure 2. The right end of valve rod 28, viewing Figure 7, is provided with female threads which are adapted to engage the male 75 threads on the rod 55. Rod 55 rests in the bear-

ing 56 contained in the cap 57, which is tightly screwed on the end of the blending valve 20. A packing 58 or any other suitable means is placed about the bearing 56 on the inside of the blending valve to prevent naphtha from escaping through the bearing 56, and a collar 59 is rigidly secured to the rod 55 adjacent the bearing 56 and on the exterior of the blending valve for the purpose of preventing any lateral movement of the rod 55. The end of the rod 55 that projects to the exterior of the blending valve is provided with a beveled gear 60 which is adapted to engage with a suitable operating means hereinafter described. The orifice plug 30 may be of the same design as those shown in Figure 2, 15 or it may be designed as shown in Figure 7. Also a screen 24a may be placed on the outlet of the blending valve to aid in further blending of the naphthas. When the beveled gear 60 is turned, the male threads on the rod 55 engage 20 the female threads in the valve rod 28 and thereby moves the valve rod 28 and the orifice plugs, which are attached thereto, back and forth in a horizontal direction, depending upon the direction of rotation of the beveled gear 60. In order 25 to limit the horizontal displacement of the rod 28 and to prevent any rotational movement of said rod 28, a tongue 61 projects into a small groove 62 contained in the top part of rod 28, thereby limiting the lateral displacement of the rod 28 to the length of the groove 62. Also the engagement of the tongue 61 with the slot 62, prevents any rotational movement of the valve rod 28.

The above manually operated blending valve is 35 operated by a dial knob 63 rigidly attached to the shaft 64, which is mounted in the bearing 65 attached to the casing of the dispensing pump, as shown in Figures 6 and 8. The end of the shaft 64 is provided with a beveled gear 66 which engages a second beveled gear 67 attached to the shaft 68. The lower end of the shaft 68 is provided with a beveled gear 69 which engages the beveled gear 60 attached to the rod 55. Shaft 68 is rotatably mounted in the bearings 70 and 71, 40 which are supported by the brackets 72 and 73 attached to the casing of the dispensing pump. Any upward or downward movement of the shaft 68 is prevented by the collars 74 and 75 attached to said shaft and on opposite sides of the bearings 50 70 and 71 respectively.

The dial knob 63 is mounted in the center of the dial 76, and a pointer 77 is attached to the knob and adapted to pass around the dial. A thermometer 78 is mounted adjacent the knob and dial so that the prevailing temperature can be observed on the thermometer and a corresponding setting can be made on the dial 76, 55 which adjusts the blending valve and admits the proper proportions of light and heavy naphtha to flow through the blending valve so as to give a gasoline with the most desirable operating properties for the prevailing temperature. For example, if the temperature is 90° F., the blending valve 20 is calibrated so that a setting of ninety on the dial 76 will give a blend of 76% heavy naphtha and 24% of light naphtha, as shown in Table II. Also if the temperature observed on the thermometer is 20° F., the blending valve is so 60 calibrated that a setting of twenty on the dial 76 will give a blend of 26% heavy naphtha and 74% of light naphtha, as shown in Table II. It should be understood that the above ratios of light and heavy naphthas are given as examples and that other ratios may be used, and if naph- 70 75

thus having boiling characteristics other than those shown in Table I are used, it will be necessary to vary the proportions of naphthas blended. Also it should be understood that the dial 5 76 may be calibrated on any basis desired, for example, it may be calibrated to show the proportions of light and heavy naphtha that are being blended at a particular temperature.

A further modification of my invention is shown 10 in Figure 9 which comprises the use of adjustable proportioning pumps. Briefly, by this modification, two reciprocable proportioning pumps are used to pump the light and heavy naphthas from the light and heavy naphtha storage tanks 15 respectively, and a means is provided whereby the length of the stroke of the pistons of each pump may be varied, thereby making it possible to vary the proportions of naphtha discharged by each pump for blending purposes. A detailed description 20 of this modification is given below.

A suitable frame 79, which is mounted on the base plate 80, is provided to support the various parts of the dispensing pump hereinafter mentioned. Conduits 81 and 82 lead to suitable naphtha storage tanks which may be similar to those shown in Figure 1. For the purpose of this description, conduits 81 and 82 will be referred to as the conduits for light and heavy naphthas respectively. The heavy naphtha conduit 82 connects with the Y 83, which leads to the two intakes of the reciprocable proportioning pump 84. The right and left intakes of the proportioning pump 84, viewing Figure 9, are commanded by check valves 85 and 86 respectively, and said valves are enclosed in housings 87 and 88 respectively. Valves 85 and 86 are pivoted at 89 and 90 respectively and are adapted to rest upon the valve seats 91 and 92 respectively; said valves swing upwardly about their respective pivots when a suction is created in the end of the cylinder 93 above each valve, otherwise the valves remain seated. A piston 94 is disposed in the cylinder 93, and a piston rod 95 is rigidly attached to said piston and is adapted to impart a rectilinear motion to piston 94. The piston rod is slidably mounted in bearing 96. The mechanism for operating the reciprocable proportioning pump will be described hereinafter. The right and left outlets of pump 84, viewing Figure 9, are commanded 45 by valves 97 and 98 respectively, and said outlet valves are enclosed in housings 99 and 100 respectively. Valves 97 and 98 are pivoted at 101 and 102 respectively and are adapted to rest upon the valve seats 103 and 104 respectively; 50 said valves swing upwardly about their respective pivots when a slight pressure is created in the end of the cylinder 84 beneath each valve, otherwise the valves remain seated. Conduits 105 and 106 lead from the outlet valves 97 and 98 respectively and terminate in the conduit 107, which leads to the conduit 108 where the naphtha from the heavy naphtha proportioning pumps is mixed or blended with the naphtha from the light naphtha proportioning pump 109.

The proportioning pump 109 draws the light naphtha in through line 81 and inlet valves 110 and 111, and forces the naphtha through the outlet valves 112 and 113. The conduits 114 and 115, which lead from the outlet valves, terminate 55 in the conduit 116. Conduit 116 connects with conduit 108, wherein the light and heavy naphthas are blended or mixed and then lead through the meter 117, visible flow-gauge 118, and dispensing hose 119. The turbulence caused during the flow of the naphthas through the conduit

108, meter 117, and visible flow-gauge 118 is sufficient to insure a homogeneous blend of the two naphthas. The two pumps 84 and 109 and related mechanism are identical, as shown in Figure 9. The means for driving the reciprocable proportioning pumps is shown in Figure 10, which shows a plan view of the mechanism of Figure 9, except for the fact that the pistons have been moved through an angle of 90 degrees. A motor 120 drives the shaft 121 which leads to the speed 10 reducing box 122. A pinion 123 is rigidly fastened to the main driving shaft 124 and is adapted to engage with a low speed driving gear in the speed reducing box 122. Driving shaft 124 is mounted in the bearings 125 and 126, which are supported by the frame work 127 that is fastened to the base plate 80 by bolts 128. A driving wheel 129 is rigidly fastened to one end of the driving shaft 124 and a similar driving wheel 130 is rigidly fastened to the other end 20 of said shaft. Each driving wheel is provided with a radially extending slot 131, as shown in detail in Figures 12 and 13. Each slot begins at a short distance from the center of the driving wheel and extends almost to the periphery 25 of said wheel. Also each slot lies in the same plane and at an angle of 180° to each other. This relative position is clearly shown in Figure 9. Figure 15 shows a guide 132, which is made of two parts and held together by the bolts 30 133, slidably mounted in slot 131 of the driving wheel 130. A similar guide is slidably mounted in slot 131 of the driving wheel 129. A radially extending rod 134 is disposed lengthwise through each slot and through the guides 132, thereby 35 providing a slide for said guides in their respective slots. Also the side ends 135 of the guides 132 project beyond the width of the respective slots and form grooves in the sides of said guides, said grooves further aid the guides in their movements within the slots 131.

Crank pins 136 and 136' (see Figures 10 and 13), are rigidly attached to the respective guides 132 which are mounted in the driving wheels 130 and 129. The crank pin 136 contained on the guide mounted in the driving wheel 130, as shown in Figure 10, is pivotally connected to the piston rod 95 of pump 84 by connecting rod 137, and the crank pin 136' contained on the guide in the driving wheel 129 is connected to piston rod 95' of pump 109 by the connecting rod 138. Any type of pivot connection 139 and 139' may be used for connecting the piston rods 95 and 95' to the respective connecting rods 137 and 138. By moving the slide guides 132 toward the periphery of the driving wheel, the length of the stroke of the respective pistons will be increased, and by moving the slide guides toward the center of the driving wheel, the length of the stroke of the respective pistons will be shortened. The longer the stroke the greater will be the discharge of naphtha from the pump per stroke; also, the shorter the stroke the smaller will be the discharge of naphtha from each piston per stroke. Therefore, by adjusting the length of the piston strokes, the proportion of naphtha pumped from the storage tanks and forced into the discharge line 108 may be varied so as to produce a gasoline of any desired blend.

In order to carry out the process described in this application, it is necessary to provide a means whereby the stroke of one piston can be made longer than the stroke of the other, so that different proportions of naphtha can be blended 75

as shown in Table II. The mechanism suitable for adjusting the length of the piston strokes comprises two splined sleeves 140 and 141 mounted on the main drive shaft 124, a plan view of said sleeves and related mechanism is shown in Figure 10, and a cross section of the sleeve 141 is shown in Figure 13.

Links 142 connect the respective splined sleeves 140 and 141 with the slidable guides in the 10 driving wheels 129 and 130. Since both splined sleeves and mechanism for operating the same are identical, the further detailed description will be given in connection with Figure 13, which shows a vertical cross section of the splined sleeve 15 141 and related mechanism for operating said sleeve. The same legends will be used on similar parts not otherwise mentioned. The link 142 is pivotally connected to the splined sleeve 141 and slidable guide 132 by pins 143 and 144 respectively. A key 145 is placed in the main drive shaft 124 so that the splined sleeve 141 will rotate with the drive shaft 124, but at the same time the sleeve can be moved lengthwise on said shaft. A shifting yoke, generally referred to by 25 legend 146, is adapted to engage with the splined sleeve 141 for the purpose of moving the said sleeve back and forth along the driving shaft 124. The shifting yoke is made in two parts, as shown in Figure 14, and is fastened together by 30 the bolts 147. The shifting yoke comprises a ball bearing collar 148 which is mounted on the main drive shaft 124 between the bearing 126 and splined sleeve 141; a sleeve 149 integral therewith, which terminates in a ring 150 that projects into the annular groove 151 contained on the left end, viewing Figure 13, of the splined sleeve 141. Ball bearings 152 and 152' are disposed between the ring 150 and the side walls of the annular groove 151, thereby forming a 35 double thrust bearing. The ball bearings 152 and 152' may be of any suitable type, for example, a ball bearing race 153, as shown in Figure 16, may be provided between the bearing surfaces of the ring 150 and the side walls of the groove 40 151. By moving the shifting yoke 146 back and forth along the main driving shaft 124, the splined sleeve is moved in a similar manner, thereby causing the guide 132 to be moved up or down in the slot 131. It should be understood that 45 a splined sleeve and shifting yoke, as above described, is used on each of the proportioning pumps for varying the length of the strokes of the respective pumps.

The mechanism for actuating the shifting yokes 50 comprises shifting levers 154 and 155, (see Figures 9 and 11), which are pivotally mounted on the bearing pivots 156 and 157 respectively. Since the mechanism for actuating the splined sleeves 140 and 141 and related elements is the same, the description of this mechanism will be given 55 in connection with lever 154 which is shown in Figure 11. The same legends will be used on similar parts not otherwise mentioned. One end of the lever 154 pivotally engages the slot 158, which is attached to the yoke 146, and the other end of said lever terminates in a fork 159, (see Figures 17 and 18 for detailed drawings). The bearings 156 and 157 are supported by the members 160 and 161, respectively, fastened to the frame 79. The lever 154 is moved from left to right, viewing 60 Figure 11, by means of a screw 162 that engages with the threads contained in the block 163, which is slidably mounted in the fork 159. The block 163 is provided with pins 164 that fit into slots 75 165 contained in the prongs of the fork 159, there-

by permitting the block 163 to move up or down for the purpose of compensating for the arcuate movement of the fork 159 when the lever 154 pivots about the bearing 156. One of the prongs of fork 159 can be removed by withdrawing the 5 screws 166, thereby providing a means whereby the block 163 can be fitted into the fork. The screw 162 is mounted in the bearing 167 contained on the support 168, which is rigidly clamped to the frame 79. The right end of the 10 screw 162, viewing Figure 11, terminates in a pinion 169. It should be understood that a lever and screw arrangement, as above described, is used on each of the splined sleeves and related mechanism. A large gear 170 is rigidly fastened to 15 one end of the shaft 171 which is mounted in the bearing 172 and is adapted to engage the two pinions 169 and 169' as shown in Figure 9. The right end of shaft 171, viewing Figure 11, projects to the exterior of dispensing pump casing 173 and 20 terminates in a hand knob 174, thereby providing a means for turning the shaft 171 and large gear 170. A pointer 175 is fastened to the knob 174 and is adapted to pass around the dial 176 which is coaxial with said knob. 25

In the operation of the reciprocable proportioning pump shown in Figures 9 to 17, the motor 120 operates the driving wheels 129 and 130 through the speed reducing box 122 and pinion 123. The pistons in pumps 84 and 109 are connected to the driving wheels 130 and 129 respectively, as shown in Figure 10, through the piston rods 95 and 95' and the connecting rods 137 and 138 respectively. The driving wheels impart a rectilinear motion to the piston of the heavy 30 naphtha pump 84 and light naphtha pump 109. The pump 84 draws heavy naphtha in through conduit 82, and the pump 109 draws light naphtha in through line 81. If the length of the strokes of the light and heavy naphtha pumps are the 35 same, each pump will discharge an equal quantity of naphtha into the blending line 108 where the two naphthas will be blended and led through the meter 117 and dispensing hose 119. The operation of the valves on the inlets and outlets of 40 pumps 84 and 109 is well known to any skilled mechanic and will only be briefly described. When the piston in the heavy naphtha pump 84 is moving to the right, viewing Figure 9, and the piston in the light naphtha pump 109 is moving 50 to the left, valves 90 and 110 open and permit heavy and light naphthas to be drawn into pumps 84 and 109 respectively; the valves 97 and 113 in pumps 84 and 109 respectively, open and permit the heavy and light naphtha to be forced into 55 lines 107 and 116 respectively. During the above operation, valves 85, 98, 111, and 112 remain seated. When the pistons in the above two pumps are moved in the reverse direction, the valves that were opened become seated, and the valves that were seated, are opened. Any suitable type of valves may be used in combination with the above pumps instead of the pivot type hereinabove described. 60

In order to vary the proportions of heavy and 65 light naphtha propelled by the heavy and light naphtha pumps, it is necessary to vary the length of the strokes of the respective pistons. With my invention this can be accomplished by turning the knob 174. When the knob 174 is turned in 70 a clockwise direction, the large gear 170 is likewise turned in a clockwise direction and said large gear imparts a counter clockwise movement to pinions 169 and 169'. The counter clockwise movement of pinion 169 causes the shifting lever 75

154 to move the splined sleeve 141 towards the driving wheel 130, thereby causing the guide 132 and crank pin 136 contained on the driving wheel 130 to be moved towards the periphery of said 5 driving wheel. The closer the crank pin 136 is to the periphery of the driving wheel 130, the longer will be the stroke of the piston in pump 84 and consequently the greater will be the amount of heavy naphtha discharged by said pump. Also 10 by the same clockwise movement of the large gear 170, a counter clockwise movement is imparted to the pinion 169 and the lever 155 will move the splined sleeve 140 away from the driving wheel 129, thereby causing the guide 132 and 15 crank pin 136 contained in the driving wheel 129 to be moved towards the center of said driving wheel. The closer the crank pin 136 is to the center of driving wheel 129, the shorter will be the stroke of the piston in pump 109 and consequently the smaller will be the amount of light 20 naphtha discharged by said pump. It should be clear that the reverse of the above movement occurs when the knob 174 is turned in a counter clockwise direction. By use of the above mechanism, the amount of heavy and light naphtha discharged from the heavy and light naphtha pumps can be varied so that a gasoline of any desired blend or volatility can be dispensed from the dispensing pump. The dial 176 may be calibrated so that the setting thereon will adjust the 25 proportioning pumps 84 and 109 to dispense a gasoline that will have the desired combustion and volatility characteristics suitable for the prevailing temperature. For example, the dial 176 30 may be calibrated so that a setting of 90 will adjust the pumps 84 and 109 to dispense a gasoline with the desired combustion characteristics suitable for use at the temperature of 90° F. The proper proportions of light and heavy naphtha 35 needed to produce a gasoline with the desired volatility and combustion characteristics for a given temperature are shown in Table II. The above reciprocable proportioning pumps can be adjusted to produce the blends set forth in Table II. 40 As another modification of my invention the pump 84 may be set to propel a constant quantity of heavy naphtha; whereas pump 109 is adjustable and can propel any proportion of light naphtha. 45 By this modification the combustion and volatility characteristics of the blended naphthas dispensed from the pump are varied by increasing or decreasing the amount of light naphtha blended with the heavy naphtha. 50 Various types of proportioning means may be used to carry out the process of simultaneously blending and dispensing naphthas in conformity with the temperature prevailing at the time of dispensing; but the hereinabove apparatus are 55 examples of satisfactory means for carrying out the process. Also light and heavy naphthas may be blended in proportions other than those set forth in Table II, but the proportions therein set forth are satisfactory for blending naphthas to 60 produce a gasoline with the most desirable combustion and volatility characteristics. 65 My invention has been described with reference to a process and apparatus for blending a plurality of naphthas with different volatilities in order to 70 prepare a gasoline with a volatility intermediate that of the naphthas, but it should be understood that I may use a plurality of naphthas or motor fuels that have any particular property or properties, and that these naphthas or motor fuels may 75 be blended in proportions to produce a gasoline

with properties common to the initial material or materials, for example, I may blend benzol and/or alcohol with naphtha at the dispensing pump in accordance with the prevailing daily temperature in order to produce gasoline with a predetermined 5 volatility, such as shown in Table II or III. Also, benzol and/or alcohol may be blended with naphtha to produce a gasoline with any property intermediate that of the initial materials.

I have described my invention with reference 10 to preferred examples, but they are not to be construed as limitations upon the scope of my invention, except as set forth in the following claims.

I claim:

1. A gasoline dispensing pump for blending a plurality of naphthas to obtain a product having a predetermined volatility and dispensing said product, comprising in combination a plurality of containers for liquid naphthas, a thermally responsive proportioning means, conduits connecting each container with said proportioning means, said proportioning means being operated in response to the atmospheric temperature for increasing the proportion of one of said naphthas 25 and decreasing the proportion of the other naphtha, an exit conduit for transferring the blended product from said proportioning means and a propelling means for moving said naphthas from the containers to the proportioning means 30 through said exit conduit.

2. A dispensing device for replenishing the fuel tank of an internal combustion engine with a motor fuel having substantially constant performance characteristics at the temperature prevailing at the time of replenishing said tank comprising, in combination, a source of light naphtha, a source of heavy naphtha, a proportioning pump for propelling the light naphtha, a second proportioning pump for propelling the heavy naphtha, a temperature sensitive mechanism responsive to changes in atmospheric temperature, means for simultaneously increasing the amount of naphtha propelled by one of said pumps and decreasing the amount of naphtha propelled by 40 the other pump in accordance with the action of said temperature sensitive mechanism, and conduits for conveying the light and heavy naphtha 45 from said pumps to a dispensing conduit.

3. A device for proportioning and mixing a plurality of volatile hydrocarbon motor fuels, comprising, in combination, a container for each of said volatile fuels, a proportioning and mixing means, a conduit connecting each container with said proportioning and mixing means, a thermally responsive means in said proportioning and mixing means for simultaneously increasing the proportion of one of said motor fuels and decreasing the proportion of the other motor fuel in response to the prevailing atmospheric temperature, means for moving the motor fuels from said 60 containers to said proportioning and mixing means, and a conduit for transferring the liquids from said proportioning and mixing means.

4. In combination with a gasoline dispensing pump comprising a measuring and recording device, and a dispensing conduit connecting with said measuring device; two supply tanks for naphthas, a proportioning means consisting of two orifices, a conduit connecting each tank with an orifice, a thermally expandible and contractable means for proportioning the flow of fluid through each orifice in response to the prevailing atmospheric temperature, and a conduit leading from said orifice and communicating with said measuring device.

5. The method of replenishing the fuel tank of an internal combustion engine with a motor fuel which comprises the following substantially simultaneous steps: withdrawing from separate sources a relatively light liquid fuel and a relatively heavy liquid fuel, mixing said fuels in predetermined proportions to obtain a combustible liquid motor fuel having the characteristics required for uniform performance of the internal combustion engine at the temperature prevailing at the time of dispensing and discharging said fuel into the fuel tank.
6. The process of replenishing the fuel tank of an internal combustion engine with a motor fuel having substantially uniform starting characteristics at different atmospheric temperatures which comprises the substantially simultaneous steps of withdrawing from separate sources liquid fuels having different starting characteristics, mixing said fuels in different proportions for each temperature to which said internal combustion engine is subjected at the time of replenishing to obtain a combustible liquid motor fuel having the starting characteristics required for the internal combustion engine at the time of replenishing the fuel tank, and simultaneously discharging said motor fuel into said fuel tank.
7. The process of replenishing the fuel tank of an internal combustion engine with a motor fuel having a different volatility at different seasonal temperatures, which comprises the substantially simultaneous steps of withdrawing from separate sources a light liquid fuel having a volatility above that required for said engine and a second liquid fuel having a volatility below that required for the engine, mixing said fuels in proportions determined by the prevailing seasonal temperature, the proportion of the heavy fuel increasing with the temperature, to obtain a combustible liquid motor fuel having the volatility required for the best performance of the internal combustion engine at the time of replenishing the fuel tank, and discharging said motor fuel into said tank.
8. A gasoline dispensing pump for blending a plurality of naphthas to obtain a fuel having a predetermined volatility and dispensing said fuel, comprising, in combination, a plurality of supply tanks for naphthas, a conduit leading from each of said tanks and terminating in a blending valve provided with a plurality of adjustable orifices, means associated with said blending valve for increasing or decreasing the flow of naphtha through one of said orifices in respect to the prevailing atmospheric temperature at the time of dispensing said motor fuel, an exit conduit for transferring the blended naphthas from said blending valve, and a propelling means for moving said naphthas from the containers to the proportioning means and through said exit conduit.
9. A gasoline dispensing pump for blending a plurality of naphthas to obtain a motor fuel, comprising, in combination, a plurality of supply tanks for naphthas, a conduit leading from each of said tanks and terminating in a blending valve provided with a plurality of adjustable orifices, means associated with said blending valve for increasing or decreasing the flow of naphtha through said orifices in response to the prevailing atmospheric temperature at the time of dispensing said motor fuel, an exit conduit for transferring the blended naphthas from said blending valve, and a propelling means for moving said naphthas from the containers to the proportioning means and through said exit conduit.
10. A gasoline dispensing device for blending two naphthas to obtain a fuel having a predetermined volatility and simultaneously dispensing said fuel, comprising, in combination, two supply tanks for naphthas, a conduit leading from each of said tanks and terminating in a blending valve provided with adjustable orifices connected to each of said supply tanks, thermally responsive means associated with said blending valve for simultaneously increasing the flow of naphtha through one of said orifices and decreasing the flow of naphtha through the other orifice in response to the prevailing atmospheric temperature, an exit conduit for transferring the blended naphthas from said blending valve, and propelling means for moving said naphthas from the containers to the proportioning means and through said exit conduit.
11. The method of dispensing a motor fuel to automotive equipment wherein a characteristic of said motor fuel is made to vary as desired in conformity with changes in atmospheric temperature prevailing at the time of dispensing, comprising simultaneously withdrawing fuels from at least two separate supplies, each supply containing a fuel of constant composition but of different characteristics from the other fuel supply, combining the fuels in a proportion automatically determined by the prevailing temperature and different for each temperature, metering the resulting fuel and transferring it to the fuel tank of said automotive equipment substantially simultaneously with said combining and metering operations.
12. The method of claim 11 wherein the characteristic which is made to vary in conformity with the atmospheric temperature is the Reid vapor pressure.
13. The method of claim 11 wherein the characteristic which is made to vary in conformity with the atmospheric temperature is the volatility as indicated by the percent evaporated at 158° F. in the A. S. T. M. distillation test.

JOHN O. EISINGER.
